UNITED STATES PATENT OFFICE.

OSCAR NORLING, OF GOTTERNBOORG, SWEDEN.

MEANS FOR SECURING TARPAULINS AND SIMILAR COVERINGS UPON SHIPS' HATCHES.

1,319,610.

Specification of Letters Patent.

Patented Oct. 21, 1919.

Application filed February 11, 1919. Serial No. 276,299.

To all whom it may concern:

Be it known that I, OSCAR NORLING, a subject of the King of Sweden, residing at Gottenborg, in the county of Gottenborg and 5 Bohus and Kingdom of Sweden, have invented new and useful Improved Means for Securing Tarpaulins and Similar Coverings upon Ships' Hatches, of which the following is a specification.

10 This invention relates to means, mainly adapted to be used for securing tarpaulins upon ships' hatches to render them waterproof in the ordinary way and also to be employed generally in such cases, where a 15 tarpaulin or other similar covering is to be closed up tightly by applying an evenly distributed pressure. The invention comprises a plurality of members adapted to be pressed perpendicularly or nearly perpendicularly 20 against and to be withdrawn from the hatch coaming in connection with which they are intended to be used. The invention is characterized mainly therein, that the clamping members are mechanically operated in a 25 slidable or rotary manner, so that when being moved toward the hatch coaming, they are caused to be rotated before the displacement so that the several pressure-surfaces move in such direction, that they intersect 30 the displacing direction, and furthermore when being withdrawn from the coaming, they are caused first to be displaced to a certain degree and then rotated, so that the pressure surfaces are removed out of the 35 displacing direction.

The invention may as mentioned above be extensively employed for sundry securing purposes, but in the following statement it will be particularly described as a means of 40 securing tarpaulins for ships' hatches. When securing such tarpaulins by hand or by means of mechanical devices, such as are commonly employed for this purpose, the tarpaulin, by the forcing of the pressing devices against it, is liable to be torn and destroyed. This trouble is avoided by the present invention, on account thereof that the pressing devices are provided in such a 45 manner. Moreover, according to this invention, all the clamping members, arranged along the same side of the hatch coaming, are united by means of a common operating device, and thus they are operated simultaneously, hence a considerable saving of

time is effected. And furthermore the sealing, ordered by the customs authorities in the case of merchant ships may easily be accomplished with adequate accuracy merely by sealing the common operating device, so that this cannot be displaced without damaging the seals.

The annexed drawings illustrate one embodiment of my invention, employed on board of ships for the purpose mentioned above. Figure 1 shows a plan view of a 65 hatch coaming provided with a securing device according to this invention, applied all around it. Fig. 2 shows a side elevation of the hatch coaming. Fig. 3 a plan view on a larger scale of a clamping member, attached 70 to the hatch coaming. Fig. 4 a front view of the same detail with the clamping-member partly in section along the line A—A in Fig. 5. Figs. 5, 6 and 7 show side views of the clamping-member in section along the 75 line B—B in Fig. 4 in different operating positions.

The clamping device 1 is provided with a cylindrical disk 2, eccentrically fixed upon a shaft 4, journaled along the hatch coaming 3, this shaft being supported by bearings 5, placed at suitable intermediate distances, and as shown in the drawing, each bearing being attached close to a clamping-member. The eccentric disk 2 is fitted in a U-shaped 80 member of a guiding block 6 reciprocable in a direction at right angles to the shaft 4, which block is provided with an oblong hole 19, extending parallel to the reciprocating direction of the guiding block, the said 85 shaft 4 passing through the hole 19. All the guiding blocks on the same side of the hatch coaming are secured to an iron batten-bar 7, extending along the entire side of the hatch coaming, which iron-bar should properly 90 be slightly bent outward opposite to each clamping-member, as shown in Fig. 1. With this arrangement the batten bars 7 may be pressed closely against the hatch-coaming along the whole length of the same, 95 and the interspace between two clamping-members may be lengthened and thus the number of members be decreased. The eccentric 2 is provided with a pin 8 projecting sideward, which pin is attached at the opposite side of the center of the disk 2 relative to the shaft 4. This pin projects from the side into either of two grooves 9 and 9^a, pro-

vided in one side of the U-shaped portion of the guiding-block 6 forming right angles with the shaft 4, said grooves being curved in a suitable manner and ended by levels 10 5 and 11 on each side of the shaft 4, a little below the horizontal level through the center-line of the shaft. When the pin 8 on account of the rotation of the eccentric 2 in the same direction as the hands of a clock, 10 see Figs. 5-7, has reached the end level 11 of the groove 9^a, it carries with it the guiding block 6 in the rotary movement when continued and thus serves as a conveyer. The rotation of the guiding block 6 in the 15 direction from the hatch-coaming (see the arrow in Fig. 7) is limited by a pin 12, provided on the bearing-bracket 5 and projecting from its side, and thus the rotation of the eccentric 2 in this direction will also be 20 stopped.

All the shafts 4, 4^a, 4^b, and 4^c provided around the hatch are at the corners of the hatch-coaming joined by means of bevel-gears 13. One of the shafts in the drawing, 25 4^a, is provided with a wormwheel 14, meshing with a worm 16, operated by means of a crank 15.

The device operates in the following manner:

30 Supposing the system to be in the position, shown by Fig. 5, the tarpaulin 17 has been pulled down between the hatch-coaming 3 and the batten-bar 7, which together with the guiding block 6 is in its withdrawn position. When operating the handle 15 all the shafts 4, 4^a, etc., are rotated to the left (according to Fig. 5) and at the same time the guiding blocks 6, projecting over the eccentrics 2, together with the batten-bars 7 35 are turned and after that moved toward the tarpaulin 13, which thereby is clamped against the hatch-coaming 3 (see Fig. 6). The tarpaulin is loosened by rotating the shafts 4, 4^a, &c., to the right from the position shown in Fig. 6, so that the parts first 40 return to the position, shown in Fig. 5, when the pin 8 of the eccentric 2 touches the bottom level of the groove 9^a. By the continued rotation of the shaft to the right, the 45 guiding blocks 6 and the batten-bars 7 are carried along with the shaft, until all these parts occupy the positions, shown in Fig. 7, when the continued rotation of the guiding blocks 6 to the right is stopped by the pin 50 12. Now the tarpaulin may easily be withdrawn.

The tarpaulin having again been spread over the hatch, the shafts 4, 4^a, &c., with the eccentrics 2 are rotated to the left from the 60 position, shown in Fig. 7, whereby the guiding-blocks 6 owing to the overweight of the batten bars 7 applied to their upturned ends are gradually collapsed to the position, shown in Fig. 5, as soon as the pin 8 of the 65 eccentric releases its pressure against the

end level 11 of the groove 9^a. By the continued rotation of the eccentrics 2 the guiding blocks 6 with the batten bars 7 are moved toward the tarpaulin and press it against the hatch-coaming in the manner 70 described above. When the hatch is to be sealed for instance by the custom-house officers in order to prevent undue opening of the same, it is sufficient merely to seal the crank 15 or to secure in any adequate manner 75 the worm-gear 14, 16.

I do not want to limit myself to the embodiment described above and illustrated in the drawing, but the details may be varied within the scope of the invention. 80

By reason of the fact that the grooves 9 and 9^a are both located in the guiding block 6, and the eccentric always touches the block 6 on two diametrically opposite sides (see Fig. 2) the block will be positively rectilinearly displaced by means of the eccentric 2, since as soon as the eccentric is revolved and its center displaced on account of the eccentric movement thereof the block 6 will accordingly be moved laterally in the same 85 degree as the pin 8 during the swinging motion thereof. Owing to the fact, that said grooves are provided at about the same distance from the center line of the eccentric 2, the pin 8, when swinging for instance away 90 from the groove 9 to the groove 9^a will not go beyond the last mentioned groove but precisely into the same. 95

Having now particularly described and ascertained the nature of my said invention, 100 and in what manner the same is to be performed, I declare that what I claim is:

1. A device of the character described including in combination, a hatch coaming, batten bars for coacting therewith, rotatable shafts, arranged in spaced relation and outwardly of the coaming and co-operative interengaging clamping members secured respectively to the bars and the shafts and designed to coact with the bars so that upon 105 rotation of the shafts in one direction the bars will be first swung and subsequently moved laterally into clamping relation with respect to the covering which is adapted to overlie the coaming and when the shaft is 110 rotated in the opposite direction these clamping members will be first moved laterally away from the coaming and subsequently swung into non-clamping position thereby obviating wear on the hatch covering. 115

2. A device as claimed in claim 1 wherein the clamping members each include a reciprocable guiding block, and an eccentric working in connection with the guiding 120 block and actuating it so that when the eccentric rotates in either direction the guiding block is withdrawn from or pressed against the hatch coaming. 125

3. A device of the character described in- 130

cluding in combination a hatch, a coaming therefor, shafts rotatably mounted on the sides of the hatch but spaced outwardly therefrom, a plurality of sets of coöperative clamping members each including an eccentric on the shaft a reciprocable guiding block of U shaped configuration the eccentric being fitted in the space between the diametrically opposite sides of the block so that the guiding block will always be in contact with two points of the eccentric during rotation of the eccentric.

4. A device as claimed in claim 3 wherein each guiding block is provided with an oblong hole through which the adjacent shaft passes so as to be guided by said shaft when being moved toward or withdrawn from the hatch coaming.

5. A device as claimed in the claim 3, wherein coöperative means is provided on the eccentric and on the block so that the eccentric after being rotated a certain angle

carries the guiding block along with it during the continued rotary movement.

6. A device as claimed in claim 3 wherein each guiding block is mounted so as to also be capable of rotating and a stationary member for limiting the rotation of the guiding block with relation to the hatch coaming.

7. A device as claimed in claim 3 wherein batten bars are provided for clamping a tarpaulin against the hatch coaming, and means for rigidly fastening the bars to the guiding blocks along each side of the hatch so that the bars will follow the combined movements of the guiding blocks.

In testimony whereof I have affixed my signature in presence of two witnesses.

OSCAR NORLING.
